H. B. WOLFE

MOP

Filed Aug. 27, 1923

INVENTOR.

H. B. WOLFE
Joseph B. Gardner
ATTORNEY.

UNITED STATES PATENT OFFICE.

HARRY B. WOLFE, OF OAKLAND, CALIFORNIA, ASSIGNOR OF ONE-HALF TO RUDOLF WEDLER, OF IONE, CALIFORNIA.

MOP.

Application filed August 27, 1923. Serial No. 659,527.

To all whom it may concern:

Be it known that I, HARRY B. WOLFE, a citizen of the United States, and a resident of Oakland, county of Alameda, State of California, have invented a new and useful 5 Mop, of which the following is a specification.

My invention relates to a mop of the self-wringing type.

10 An object of the invention is to provide a mop in which the compressibility of the cloth is utilized to provide the desired resiliency of the wringing pressure, thereby eliminating the use of springs.

15 Another object of my invention is to provide a mop of the self-wringing type in which practically the full length and width of the mopping cloth can be used in the mopping operation.

20 A further object is to provide a mop in which the length of cloth available for use in a mopping operation may be varied as desired, and which may be used as a scraper without changing the position of the 25 mounting of the mop cloth or adding an extra member.

20 A still further object of my invention is to provide a mop of the character described in which a mop-cloth of any desired material 30 or form may be inserted and used without difficulty.

35 My invention possesses other objects and features of advantage, some of which, with the foregoing, will be set forth in the following description of the preferred form of my invention which is illustrated in the drawings accompanying and forming part of the specification. It is to be understood that I do not limit myself to the showing 40 made by the said drawings and description, as I may adopt such variations of the preferred form as fall within the scope of my invention as set forth in the claims.

45 Referring to said drawings:

45 Figure 1 is an end elevation of the mop in position for use, the stick or handle portion being broken away.

Figure 2 is a side view of the upper side of the mop as shown in Figure 1.

50 Figure 3 is a section of the mop taken on the line 3—3 in Figure 2.

Figure 4 is an enlarged section of one of the rolls of the device taken on the line 3—3 in Figure 2.

Briefly expressed the mop in its present embodiment comprises a frame supporting a pair of spaced parallel rolls around which passes a belt to which one end of the mop-cloth is attached. A pair of parallel rollers is carried on the frame, one of the rollers being positioned to cooperate with one of the rolls so that upon movement of the belt the cloth will be passed between the roll and roller and the water expressed therefrom, the other roller engaging the belt in such manner that pressure between the first mentioned roll and roller will be maintained. The said first roll and roller are carried at the lower end of the frame so as to allow a maximum amount of the cloth to be available for the mopping operation. Hand operated means are provided for rotating the rolls. Means are also included for holding the cloth in the most effective position for use.

75 A detailed description follows:

The mop as here shown comprises a rectangular frame 2 to the upper cross member 3 of which is attached a suitable handle 4. Rotatably mounted adjacent the ends 3 and 5 of the frame are rolls 7 and 8 which are disposed in parallel relation to the ends of the frame. Circumferential belt grooves 9 are provided in the rolls in which an endless and relatively inelastic belt 11 is adapted to fit, the groove being of such depth that the outer surface of the belt will be flush with the surfaces of the rolls. Rotation of the roll 7 is preferably effected by means of the crank 12 which is fixed to the roll 7, the surface of groove 9 in roll 7 being provided with teeth 10 to insure a non-slipping engagement with the belt.

85 Suitably attached to belt 11 is a stirrup 14 in which a mop-cloth 13 is adapted to be held, said stirrup comprising flexible side members 14 and a relatively stiff cross member 15, and is secured on the outer side of the belt for movement therewith.

90 Pressure means are provided which are adapted to co-operate with the roll 8 for wringing the cloth upon appropriate move-

ment of the belt. As here shown, similar levers 16 are oppositely pivoted in the sides of frame 2, and rollers 17 and 18 are rotatably mounted in parallel relation on and between the corresponding ends of the levers. The pivoting of the levers 16 is so positioned that the roller 18 is normally in contact with the roll 8. The belt 11, being disposed about the members 8, 7, and 17, is of such length that it will be caused to tighten as roll 8 and roller 18 are caused to separate, thus resisting the separation of roll 8 and roller 18.

It will now be clear that, as the crank 12 is turned to draw the belt 11 around the rolls 8, 7 and 17, the stirrup 14 and cloth 13 will be drawn between the roll 8 and roller 18, so that whatever surplus liquid may be contained in the cloth will be effectively expressed therefrom. It will be readily understood that the mop, due to the thickness of the cloth and contained water, will tend to separate the rolls 8 and 18, such separation being resisted on account of the engagement of the roller 17 with the belt, the wringing pressure on the mop thus increasing with an increase in the thickness of the mop.

After the wringing operation is completed the crank is turned to allow a portion of the cloth to be held between the members 8 and 18 thus securely holding the cloth for use, any desired amount being left below the roll 8 for the mopping operation. The cloth is preferably made no longer than the belt so that there will be no possible overlapping of the ends as the belt is drawn around the rolls.

The end 5 of the frame 2, which is formed parallel to the roll 8, serves as a bearing member for the mop-cloth 14. When the mop is in use, the cloth is normally positioned between the roll 8 and end 5, and a portion of the end of the cloth is then positioned under the end 5 and doubled back between the bearing end 5 and the surface to be cleaned. In this manner the pressure exerted by the operator is communicated through the frame end and does not affect the mop wringing and positioning mechanism. Furthermore, the member 5, when it has no cloth between it and the surface to be cleaned, is adapted for use as a scraper to loosen dirt adhering to the said surface.

The mop-cloth 13 may be of any desired material or form, and if of continuous belt form may be readily placed about the stirrup member 15 by detaching one of the members 14 therefrom. It will thus be evident that the device of my invention remains assembled during all operations including that of securing the mop-cloth therein. The stirrup bar 15 may be formed to mechanically grip the mop-cloth, or the cloth may be merely looped about it.

I claim:

1. A mop comprising a rectangular frame, a pair of rolls mounted in spaced parallel relation in said frame, an endless belt passing around said rolls, a mopping cloth secured adjacent one end to said belt and adapted to move therewith over said rolls, and means actuated by said belt adapted to resiliently press against said cloth as it moves over one of said rolls. 70

2. A mop comprising a rectangular frame, a pair of rolls rotatably mounted in spaced parallel relation inside said frame, an endless belt passing around said rolls, a mop-cloth attached adjacent one end to said belt and adapted to move therewith over said rolls, a pressure roll cooperating with one of said first rolls and arranged to engage said cloth, means for rotating one of said first rolls, and means associated with said belt for imparting pressure to said pressure roll. 80

3. A mop comprising a frame, a pair of rolls rotatably mounted in spaced relation in said frame, an endless belt passing around said rolls, a mop-cloth attached adjacent one end to said belt and adapted to lie on the outer side thereof, said cloth being shorter than said belt, means for rotating one of said rolls, and a roll carried by said frame 90 and adapted to bear against one of said first rolls so as to engage said mop-cloth with a pressure. 95

4. A mop comprising a one piece rectangular frame, a pair of rolls rotatably mounted in parallel relation adjacent the upper and lower ends of said frame, a belt passing around the pair of rolls, a mop-cloth secured at one end to said belt, means for rotating the roll disposed at the upper end of said frame, a roller adapted to cooperate with the roll disposed at the lower end of the frame whereby said cloth may be passed between said last roll and said roller, and means actuated by said belt and cloth for exerting a pressure on said cloth as it is passed between said roll and roller. 105

5. A mop of the character described comprising a one piece rectangular frame, a pair of rolls rotatably mounted in parallel relation adjacent opposite ends of said frame, a pair of levers pivoted for rotation at opposite points on the sides of said frame, a second pair of parallelly disposed rolls mounted on and connecting corresponding lever ends one of said latter rolls being adapted to contact with one of said first mentioned rolls, a continuous belt passing around the other of said latter rolls and the first mentioned pair of rolls, a mop-cloth attached to said belt for motion therewith, and means for drawing said belt around said rolls. 115

6. A mop of the character described comprising a frame, a pair of rolls mounted in 120

spaced parallel relation in said frame, levers pivoted for rotation at opposite points of the frame, a second pair of parallelly disposed rolls mounted on said levers, one of said latter rolls being in cooperative relation with one of said first rolls, and a continuous belt passing around the other of

said second rolls and the first mentioned rolls.

In testimony whereof, I have hereunto set **10**
my hand at Oakland, this 18th day of July,
1923.

HARRY B. WOLFE.
